UNITED STATES PATENT OFFICE.

CHARLES T. TARPPENNING, OF INDIANAPOLIS, INDIANA, ASSIGNOR OF ONE-HALF TO
BERTSCH & COMPANY, OF CAMBRIDGE CITY, INDIANA, A CORPORATION.

SHEET-METAL-BENDING MACHINE.

1,127,109.

Specification of Letters Patent. Patented Feb. 2, 1915.

Application filed February 17, 1914. Serial No. 219,260.

To all whom it may concern:

Be it known that I, CHARLES T. TARPPENNING, a citizen of the United States residing at Indianapolis, in the county of Marion and State of Indiana, have invented certain new and useful Improvements in Sheet-Metal-Bending Machines, of which the following is a specification.

This invention relates to a machine for bending sheet metal, to form ridge rolls, gutters, and valleys used for roofing purposes, and is an improvement on my U. S. Letters Patent No. 724,519, issued April 7, 1908.

15 The object of the invention consists in the provision of a machine of the above character in which the greatest force is applied to the crimping jaws when the latter are brought directly into contact with the tem-
20 plet of the machine.

A further object of the invention is to provide a machine of the above character whereby different forms in sheet metal may be produced, and whereby said metal may 25 be uniformly and accurately formed for the purposes for which the same is intended.

I accomplish the above objects of the invention by means of the device illustrated in the accompanying drawings, forming a part 30 hereof, in which—

Figure 1 is a fragmentary detail view in side elevation of the front and right-hand end of the machine for bending sheet metal. Fig. 2 is a cross section on the line 2—2 in 35 Fig. 1. Fig. 3 is a view similar to Fig. 2 except that the parts have been moved to the end of their inward travel in forming the metal sheet. Fig. 4 is a detail in cross section on the line 4—4 in Fig. 1.

40 Referring to the drawings, the machine comprises a frame in which 10 represents an end member, one of which is arranged at each end of the machine, the two end members being held in rigid relation by means of the connecting beams 11 and 12. Arranged immediately below and secured to the beam 11 by means of suitable bolts 14 is the templet 16, the formation of which im-
45 parts the various desired curves to the sheet metal to be bent. A transverse view of the templet 16 is shown in Figs. 2 and 3 and upon this style of a templet ridge rolls for roofing purposes are produced. Coöperating 50 with the templet 16 is a movable clamp,

consisting of a parallel pressure-bar 18 55 having a depression therein corresponding to the exterior formation of the adjacent face of the templet 16. The bar 18 is suitably supported by means of a plurality of yokes 19, and these yokes form seats for the 60 bolts 20. Slotted blocks 21 are secured to the bolts 20, the former providing housings for the anti-friction rollers 22 which in turn bear against the peripheries of the 23 65 which are arranged upon the main drive 61 shaft 24, and these cams provide the means by which the pressure-bar 18 is moved against the lower adjacent surface of the templet 16. These cams have sufficient and prolonged high portions to move and hold 70 the pressure-bar 18 against the templet 16 to force the sheet metal into the depression in the face of said bar and to continue to firmly hold the said metal sheet against the templet during the remaining operation 75 of bending the sheet metal against the side faces of the templet 16. The adjustment of the bar 18 with respect to the templet 16, so that proper registration may be secured and maintained, is effected by means of the bolts 80 20 and the lock-nuts 25. The free ends of the metal sheet 29 are bent to conform to the irregularities in the sides of the templet 16 by means of the die plates 30, one of which is located on each side of the templet 85 16. These die plates are supported at intervals by means of the arms 31, and these arms are supported on a suitable shaft 32 which is anchored in the end members 10, 90 10 of the frame of the machine.

In order to secure and maintain accurate registration between the die plates 30 and the templet 16, I provide an adjusting means consisting of suitable supports 33 which are pivotally connected to the arms 31 at 34. 95 These supports 33 are actuated by suitable toggles and the supports move the arms 31 and the die plates 30, and by means of the set screws 36, arranged in the arms 31 and resting upon the supports 33, the distance 100 between the free ends of the arms and supports may be changed to vary, regulate and maintain the desired throw of the die plates 30. The toggles for actuating the arms 31 and for moving the die plates 30 against the 105 faces of the templet 16 comprise two connecting links 40 and 41, the former pivotally engaging the supports 33 at 43 and the

latter pivotally engaging the ears 44 which are formed integrally with the connecting beam 12 of the frame of the machine.

When the parts occupy the position shown 5 in Fig. 2, which is the open position of the machine and which allows the metal sheet 29 to be inserted into the machine, as shown, the movable parts may be elevated into the position shown in Fig. 3, to crimp the metal 10 sheet around the exterior surface of the templet 16, by means of a pair of cams 50 and 51 which are secured to the main shaft 24. These cams operate the connecting arms 53 and 54 which engage the toggles at 55, the 15 cams 50 and 51 being arranged on the main shaft 24 to simultaneously move the connecting arms 53 and 54 inwardly at each revolution of the cams 50 and 51. The use of toggles for raising the arms 31 and the die 20 plates 30, enables a gradually increasing application of power to be applied against the die plates 30 until the links of the toggles more nearly approach a straight line, thereby 25 enabling the greatest pressure to be applied at the time the die plates 30 are in contact with and in the final act of bending the metal sheet around the irregular external surface of the templet 16. This construction has a decided advantage over the 30 one heretofore used by me, in which the arms 31 and die plates 30 are actuated by the use of cams, wherein the amount of power exerted increases on the approach of the greatest radii of the cams, but which 35 power cannot be maintained during the operation of crimping the remaining portion of the metal sheets caused by the decrease in the radii of the cams as they continue to rotate.

40 The machine may be driven by any suitable means for applying power to the main drive shaft 24, and, for convenience, I have shown a pulley 60 rotated by a belt 61; and by means of the clutch 62 of any preferred 45 type, which clutch is actuated by means of a hand-lever 63, the rotating parts may be thrown into and out of operation when desired.

50 The standard length of galvanized iron is ten feet, and the machine is made of a length to enable material of the above-mentioned length to be fed therein. As shown in Fig. 2 of the drawings, a suitable gage 70 is provided to limit and regulate the insertion 55 of the metal sheets, so that the templet will always come into contact with the center of the sheets. After a sheet of metal has been bent into the desired form and the die plates 30 are in their lowest position, as 60 shown in Fig. 2, the irregularly formed finished product is easily removed by moving the same longitudinally along said templet 16 and out of the machine. As a ten foot length of sheet metal is formed into a finished product at each operation of the die 65

plates 30, which have a rhythmical intermittent stroke, a vast amount of accurately and uniformly finished product can be produced within a limited period of time.

Having thus fully described my said invention, what I desire to secure by Letters Patent is—

1. In a bending machine, the combination with the main frame, of a templet arranged in said frame, a pressure-bar arranged beneath and for holding the metal sheets against the templet, means for moving said pressure-bar into contact with said templet, means for regulating the movement of the pressure-bar toward the templet, a pair of swinging jaws arranged to coöperate with said templet, toggles for the jaws, means for changing the position of the jaws with respect to the toggles, and means for actuating said toggles. 75

2. In a bending machine, the combination with the main frame, of a templet arranged in said frame, a pressure-bar arranged beneath and for holding the metal sheets against the templet, means for moving said pressure-bar into contact with said templet, a pair of swinging jaws arranged to coöperate with said templet, a pair of toggles for raising the jaws into contact with said templet, means independent of the toggles 90 for regulating the travel of said jaws, and means for actuating said toggles. 95

3. In a bending machine, the combination with the main frame, of a templet rigidly secured in said frame, a pressure-bar arranged beneath to coöperate with said templet, means for actuating said pressure-bar, a pair of swinging jaws arranged to coöperate with said templet, a pair of toggles, for raising the jaws into contact with said 100 templet, supports arranged intermediate of and pivotally engaging both the toggles and jaws, adjusting-means independent of the supports for regulating the pressure of the jaws against the templet, and means for imparting movement to said toggles. 105

4. In a bending machine, the combination with the main frame, of a templet arranged in said frame, a pressure-bar for supporting and clamping the metal sheets against said templet, means for moving said pressure-bar against said templet, means for regulating the introduction of the metal sheets into the machine, a pair of swinging jaws arranged to coöperate with said templet, adjusting 115 means independent of the toggles for controlling the pressure of the jaws against the templet, a pair of toggles for elevating the jaws into contact with said templet, and means for actuating said toggles. 120

5. In a bending machine, the combination with the main frame, of a templet arranged in said frame, a pressure-bar for supporting and clamping the metal sheets against said templet, means for moving said pressure-bar 125

against said templet, means for regulating the introduction of the metal sheets into the machine, a pair of swinging jaws arranged to coöperate with said templet, means arranged on the jaws for controlling the pressure for varying the travel of said jaws, and means for actuating said toggles.

In witness whereof, I have hereunto set

my hand and seal at Indianapolis, Indiana, this 2nd day of February, A. D. one thousand nine hundred and fourteen.

CHARLES T. TAPENNING. [L. & J.]
